INVENTOR:

Jacob B. Campbell

UNITED STATES PATENT OFFICE.

JACOB B. CAMPBELL, OF YONKERS, NEW YORK.

DESIGN FOR CARPET.

SPECIFICATION forming part of Design No. 25,222, dated March 3, 1896.
Application filed January 31, 1896. Serial No. 577,625. Term of patent 3½ years.

To all whom it may concern:

Be it known that I, JACOB B. CAMPBELL, a citizen of the United States, residing at Yonkers, in the county of Westchester and State of New York, have invented and produced a new and original Design for Carpets, of which the following is a specification.

My invention relates to a design to be worked into or upon carpeting or similar fabrics; and I do hereby declare that the drawing accompanying this specification gives and conveys to any one skilled in the art of carpet-weaving a clear understanding of the same that is sufficient to enable such person to use my invention.

The said drawing is a face view of a carpet embodying my new design.

The drawing illustrates a body and a border.

The body A consists of a substantially uniform groundwork upon which are arranged small figures, and these figures form a design known as "Indian" in style.

The border B consists of a substantially uniform groundwork upon which appear the

same figures and same arrangement as in the body A. The outer margin consists of scroll-work drawn in scallop fashion, upon which appear to stand sprigs of leaves in vertical fashion. Beyond this appear figures of so-called "Indian" design, alternating in regular series, all substantially as shown.

The colors employed for the different portions of this design may be varied to suit the convenience or taste of the manufacturer.

What I claim, and desire to secure by Letters Patent, is—

1. In a design for carpeting, the body A, substantially as shown.
2. In a design for carpeting, the border B, substantially as shown.
3. The design for carpets, consisting of the body A and the border B, substantially as shown.

JACOB B. CAMPBELL.
